United States Patent Office.

CHARLES B. CLARK, OF BUFFALO, NEW YORK.

Design No. 4,855, dated May 2, 1871.

DESIGN FOR A GATE-HINGE.

The Schedule referred to in these Letters Patent and making part of the same.

I, CHARLES B. CLARK, of the city of Buffalo, in the county of Erie and State of New York, have invented and produced a new and original Design for a Gate-Hinge, of which the following is a specification.

The nature of my design is fully represented in the accompanying drawing, in which—

Figure I is a perspective view of the upper hinge of a gate.

Figure II is a perspective view of the portion thereof which is to be attached to the post.

Similar letters denote like parts in the two figures.

A represents the portion of the hinge which is to be attached to the gate, and

B the other portion which is attached to the post.

The portion A is provided with a bracket and cone-

shaped cap, a, covering the cone-shaped pintle b of the other portion of the hinge, the other parts of the design being represented by the letters b¹, b², and e, all taken together forming a new and original design, of which the cone-shaped cap and pintle form a characteristic feature.

What I claim, and desire to secure by Letters Patent, is—

The design for a gate-hinge, as herein shown and described.

CHARLES B. CLARK.
